(57) **CLAIM**

The ornamental design for a accessory clamshell design, substantially as shown and described.

DESCRIPTION

FIG. 1 is a perspective view of an embodiment of the inventive accessory clamshell design on a container illustrating the pear-shaped feature together with two bars transversing the pear-shaped feature.

FIG. 2 is a front view thereof;

FIG. 3 is a back view thereof;

FIG. 4 is a side view thereof;

FIG. 5 is the opposite side view thereof;

FIG. 6 is a top view thereof;

FIG. 7 is a bottom view thereof;

FIG. 8 is a perspective view of another embodiment of the accessory clamshell design illustrating the pear-shaped feature together with seven transversing bars;

FIG. 9 is a perspective view of another embodiment of the accessory clamshell design; and,

FIG. 10 illustrates a container having the accessory clamshell design embodied in FIG. 9 in its open position.

The broken lines are for illustrative purpose only and forms no part of the claimed design. The inside boundary of the clamshell package is defined by the broken lines around the blister.
